UNITED STATES PATENT OFFICE.

CHARLES F. LOOMIS, OF WINONA, MINNESOTA, ASSIGNOR TO THE WESTERN INDURATED FIBRE COMPANY, OF SAME PLACE.

FASTENING FOR PAIL-COVERS.

SPECIFICATION forming part of Letters Patent No. 379,797, dated March 20, 1888.

Application filed December 24, 1887. Serial No. 258,934. (No model.)

To all whom it may concern:

Be it known that I, CHARLES F. LOOMIS, a citizen of the United States, and a resident of Winona, in the county of Winona and State of Minnesota, have invented certain new and useful Improvements in Fastenings for Pail-Covers; and I do hereby declare that the following is a full, clear, and exact description of the invention, which will enable others skilled in the art to which it appertains to make and use the same, reference being had to the accompanying drawings, which form a part of this specification, and in which—

Figure 1 is a perspective view of as much of a pail and its cover as will be sufficient to illustrate the construction of the preferred form of my fastener. Fig. 2 is a similar view showing a slightly-modified form of the fastening-strip. Fig. 3 is a similar view showing a modified form of the ear for the bail. Fig. 4 is a detail view of the preferred form of the strip. Fig. 5 is a similar view of the preferred form of the ear for fastening the bail. Fig. 6 is a perspective view of a modified form of fastening; and Fig. 7 is a bottom perspective view of one of the ears, showing one style of the recess in full line and another style in dotted lines.

The same numerals of reference indicate the same or corresponding parts in all the figures.

My invention has relation to fastenings for the covers or lids of pails or similar packages; and it consists in the improved construction and combination of parts of a fastening, which is especially adapted to be applied to pails made of pulp or similar material, and which is adapted to be secured to the pail by the ears fastening the bail or handle, as will be more fully described, and particularly pointed out in the claims.

In the accompanying drawings, the numeral 1 indicates the side of the pail or package, having the lid or cover 2, which may be of any suitable material and of any suitable construction.

The bail or handle 3 of the pail has its hooked ends 4 inserted into a central perforation, 5, in the bulged central portion, 6, of the ears 7, which are secured to the pail by rivets 8 passing through the sides of the pail and through laterally-projecting lips 9. The fastening-

strip 10, which may be either flat or round—being, however, preferably flat—is inserted through apertures 11 in the upper and lower portions of the bulged portion of the ear. The 55 strip has its lower end bent straight across when the strip is flat, to form a lip or stop, 12, while its upper end is secured to the lid or cover by nails or tacks driven through it and the cover, by staples having the strip passed 60 through them and doubled over them, or by any other suitable fastening means.

In Figs. 1 and 2 the apertures in the bulged portion of the ear are formed in the edge of the same, being notches or recesses, and the 65 strip, which in Fig. 1 is shown flat and in Fig. 2 is shown as a piece of wire, is held in these notches between the ear and the side of the pail, having the lip or stop at its lower end, preventing the strip from slipping up through 70 the apertures.

In Fig. 3 of the drawings the strip is shown passed through slots in the ear, being otherwise secured in the same manner as in the other form.

Whenever a strip is broken or otherwise rendered unfit for use, another strip may easily be inserted after having withdrawn the former strip, and the lower end of the strip being bent to form the stop or lip, the strip will be held 80 from slipping up through the apertures in the diametrically-opposite edges of the ear.

The strip may be secured by the ear, without having the edges of the latter notched or recessed, by simply inserting the strip between 85 the ear and the side of the pail, as shown in Fig. 6, when the ear will clamp the strip between it and the side of the pail and will retain it, the lower end of the strip being bent up, as before stated, holding against the lower 90 edge of the ear.

It will be seen that this fastening may be used for any vessel having a handle or handles, the handle or handles being secured with their hooked ends in the ears which secure the 95 strips, or being formed integral with the ears or riveted or otherwise secured to the same, so that the fastening may be used for tubs or other vessels having two or more handles or having only one handle at one side, as well as 100 for pails having one handle secured at opposite sides; and any suitable means for securing

the free upper end of the fastening-strip may be used, such as tacks, staples, or any other kind of fastening.

By reference to the drawings it will be seen that the lower edge of the lower recess or notch, which is preferably formed by striking up the metal at the points for the recesses or notches, is rounded, and the line at which the lip or stop of the strip is bent is straight, causing the fold at the lip to bear against only one part of the curved edge of the notch or recess, and this construction will prevent the edge of the recess from cutting the bent end or lip off from the strip when strain is exerted upon the strip, which would be liable to happen if the edge were straight or if the lip were bent upon a curved line corresponding to the curve of the edge.

This fastening is especially adapted to vessels or packages made from wood pulp or other fiber, from any kind of hard compressed or molded material, or from metal, all of which materials are sufficiently hard to render it difficult, if not impossible, to drive nails or tacks into; and the fastening will also be advantageous for wooden vessels, in which nails or tacks may easily be driven, as it will save the vessel and prevent its being damaged by driving the nails or tacks into its sides.

The insertion of the strip and the number and location of the apertures in the bulged part of the ear may be modified in various ways, and the ear may be provided with various forms of passages for the insertion of the

strip, without departing from the spirit of my invention, and I do not wish to confine myself to the exact construction of the fastenings shown in the drawings.

Having thus described my invention, I claim and desire to secure by Letters Patent of the United States—

1. The combination, with a pail having ears upon its sides, of fastening-strips secured thereto, the lower ends of which are bent and engage with the ears of the pail. 45

2. The combination, with a pail the ears of which are round upon their lower edges, of fastening-strips secured thereto, the lower ends of which are bent straight across and engage with the lower edges of the ears. 50

3. The combination, with a pail the ears of which are recessed, of fastening-strips secured thereto, the lower ends of which are bent and engage with the recessed portions of the ears.

4. The combination, with a pail the ears of which are recessed in their bulged portions, of fastening-strips passed through said recessed portions and having their lower ends bent and engaging with the lower edges of said recessed portions. 55

In testimony that I claim the foregoing as my own I have hereinunto affixed my signature in presence of two witnesses.

CHARLES F. LOOMIS.
